W. DUNCAN

SCALP MASSAGING DEVICE

Filed July 25, 1924

Fig. 1.

Fig. 2.

Inventor:
W. Duncan,

by Hazard and Miller

Attorneys

UNITED STATES PATENT OFFICE.

WILLIAM DUNCAN, OF LOS ANGELES, CALIFORNIA.

SCALP-MASSAGING DEVICE.

Application filed July 25, 1924. Serial No. 728,184.

To all whom it may concern:

Be it known that I, WILLIAM DUNCAN, a citizen of the United States, residing at Los Angeles, in the county of Los Angeles and State of California, have invented new and useful Improvements in Scalp-Massaging Devices, of which the following is a specification.

This invention relates to scalp massaging devices.

It is an object of the invention to provide a circular scalp massage comb with a handle, such that the comb will be pivoted upon said handle.

It is a further object of the invention to provide a scalp massaging device consisting of a handle, a comb pivoted upon such handle so as to be adjustable with respect to the handle and to provide resilient restraining means for the device, such that the comb will be urged to assume a normal predetermined position.

It is another object of the invention to provide a cheap, simple and durable device which may be easily and quickly manipulated and which will adjust itself to the desired position.

With the foregoing and other objects in view which will be more specifically pointed out in the following detailed description and defined in the appended claims, reference is had to the accompanying drawing for an illustrative embodiment of the preferred form, wherein—

Fig. 1, is a top plan view of the improved device.

Fig. 2, is a side elevation of the device shown in Fig. 1.

Fig. 3, is a perspective view showing the improved device as applied.

Referring to the accompanying drawing wherein similar reference characters designate similar parts throughout, the device consists of a circular scalp comb which is of somewhat conventional construction, having a body portion 10, with integral teeth 11. Although this comb may be made of metal, it is preferably made of wood, compressed fibre, or some equivalent composition. A handle is provided for the device, formed of a single piece of wire bent as at 12, and having convergent sides 13 and 14, which sides cooperate to form a hand gripping portion. The forward ends of the convergent sides 13 and 14, are parallel as at 13'

and 14' and are outwardly flared about the comb as at 15 and 16, the ends of the handle being bent as at 17 and 18, and inserted into openings or apertures 19 and 20, formed in the body 10, of the comb. By this means, 60 the comb is pivoted upon the handle.

As a means for retaining the comb in normal position with respect to the handle, a plate 21, is secured upon the convergent sides 13 and 14, of the handle and a pair 65 of resilient members 22 and 23, are secured to the plate 21, and to the rearmost portion of the body 10, of the comb. These resilient members are preferably in the form of cloth covered rubber bands, although they 70 may be of any equivalent material which will assert tension between the plate 21, and the comb.

From the above it is seen that a device 75 is provided wherein a comb is pivoted to a handle, such that the handle may assume any position with respect to the comb upon massaging the scalp. Furthermore, means is provided for urging the comb into normal position with the plane of its body 10, 80 parallel with the plane of the handle, so that during the massaging, although the handle may assume an angular position with respect to the comb, it is continually urged into normal position by the elastic members 22 85 and 23.

It is to be understood that the accompanying drawing and the above description have been used for illustrative purposes only to illustrate the preferred form of the invention, but that various changes in the details of construction may be made without departing from the spirit or scope of the invention as defined by the appended claims.

What I claim is:

1. A device of the class described comprising a comb having a body in the form of a ring, a circular row of teeth projecting downwardly from said body, and a handle pivoted to said body.

2. A device of the class described comprising a comb having a body in the form of a ring, a circular row of teeth projecting downwardly from said body, a handle pivoted to said body, and means for resiliently retaining said comb in a predetermined position with respect to said handle.

3. A device of the class described comprising a comb having a body in the form of a ring, a circular row of teeth projecting 110

downwardly from said body, a handle pivoted to said body, and means including elastic bands for resiliently retaining said comb in a predetermined normal position with respect to said handle.

4. A device of the class described comprising a comb having a body in the form of a round ring, teeth integral with said body, a handle pivoted to said body, and elastic means for resiliently retaining said comb in a predetermined normal position with respect to said handle.

5. A device of the class described comprising a comb, a handle pivotally connected to said comb, and resilient means for urging said comb into a predetermined position with respect to said handle.

6. A device of the class described comprising a comb, a handle pivoted to said comb, and elastic means for urging said comb into

a predetermined position with respect to said handle.

7. A device of the class described, comprising a comb, a handle pivotally secured to the body of said comb and elastic members secured upon said handle and to the body of said comb, and stretched therebetween, said elastic members being adapted to urge said comb into a predetermined normal position.

8. A device of the class described, comprising a circular comb, a handle pivoted to the body of said circular comb, a plate secured upon said handle and elastic members stretched between said plate and said body of the comb adapted to retain said comb in normal position.

In testimony whereof I have signed my name to this specification.

WILLIAM DUNCAN.
